CARBAZOLE-ALKYL KETONES

Anderson W. Ralston and Carl W. Christensen,
Chicago, Ill., assignors to Armour and Company, Chicago, Ill., a corporation of Illinois

No Drawing. Application September 19, 1936,
Serial No. 101,675

5 Claims. (Cl. 260—46)

This invention relates to aralkyl ketones and it comprises, as new compounds, ketones having the generic structure

wherein R is a carbazole radical and R' is an alkyl radical having eleven, thirteen, fifteen, or seventeen carbon atoms; and it further comprises 10 diketones having the structural formula

13 wherein R is a carbazole radical and R' is an alkyl radical having eleven, thirteen, fifteen, or seventeen carbon atoms.

The higher fatty acids, and by that we mean those fatty acids derived from vegetable and animal oils and fats, are extremely abundant materials and can be obtained at little expense. They have never, however, been used to any great extent as raw materials for the synthesis of more valuable substances. These fatty acids have been used almost exclusively in the soap industry, for 25 making candles, etc., and in but relatively few instances have they been used as raw materials in what might be termed as the "fine" organic chemical field.

We have now discovered a new class of compounds which can be made from the higher fatty acids and which have chemical and physical properties of marked technical and commercial interest. We have discovered that the higher fatty acid chlorides, such as stearyl chloride, 30 myristyl chloride, lauryl chloride, caproyl chloride, and other acid chlorides derived from, and corresponding to the higher fatty acids, can be made to react with carbazole, or substituted carbazoles, to give aralkyl ketones having valuable 35 properties which suit them for use in many technical applications. These aralkyl ketones are waxy solids, and can be crystallized from organic solvents such as benzene, alcohol and others to give pure ketones. The crystalline products, when melted and allowed to cool, yield substances of clearly defined waxy character, appearance and feel. We have discovered that they are excellent dielectrics and can be used in electrical insulation. We have also discovered that 40 these new substances are desirable constituents in waxing and polishing compounds. When added to lubricating oils, the ketones of the present invention confer beneficial properties on the oil. The ketones of our invention have pronounced antifoaming properties and can thus be

added to aqueous liquids such as boiler water to prevent foaming therein.

In its broad aspects, our invention comprises new products having the generic formula

wherein R is a carbazole radical which may be substituted or not, and R' is an alkyl radical corresponding to the alkyl radical of a higher fatty acid. By higher fatty acid we mean those fatty acids having twelve or more carbon atoms. We have also discovered that diketones containing two alkyl radicals attached to a carbazole nucleus can be prepared. Thus, as an example, one 15 of the new products falling within the scope of our invention is 2-stearylcarbazole:

In this case, the C₁₇H₃₅, or heptadecyl radical, is the alkyl radical or stearic acid, C₁₇H₃₅COOH. 25 This particular ketone has a melting point of 105–106° C.

Another typical ketone falling within the generic scope of our invention is 2-laurylcara- 30 zole:

Melting point 101–102° C.

Other ketones falling within the scope of our invention are diketones prepared from carbazole and higher fatty acid chlorides. Thus, for ex- 40 ample:

2,8-distearylcarbazole (melting point 161–162° C.)

2,8-dipalmitylcarbazole (melting point 162° C.)

55

2,8-dimyristylcarbazole (melting point 169° C.)

5

2,8-dilaurylcarbazole (melting point 176° C.)

10

15 All of the ketones of our invention can be made by Friedel-Crafts reaction.

Thus, for example, when we wish to make 2-stearylcarbazole we start with carbazole and stearyl chloride. The stearyl chloride can be made in any of the known ways from stearic acid. Generally the stearic acid is treated with phosphorus pentachloride or other chlorinating reagent commonly used for converting aliphatic carboxylic acids to their corresponding acid chloride. Thirty-five parts by weight of carbazole are reacted with 50 parts of stearyl chloride, using approximately 100 parts by weight of carbon disulfide as a solvent. Hydrogen chloride is evolved and the stearyl radical thereby attached to the nitrogen, giving N-stearylcarbazole. The mixture is then cooled in an ice bath and about 50 parts by weight of aluminum chloride are added with constant stirring. This rearranges the N-stearylcarbazole to give 2-stearylcarbazole.

35 The reaction mixture is then poured onto a mixture of ice-dilute hydrochloric acid to hydrolyze any complex aluminum chloride compound formed in the reaction. Finally the resulting mixture is placed in a flask and subjected to 40 steam distillation. This removes the carbon disulfide used as a solvent and also any excess carbazole. The ketone does not distill over with the carbon disulfide and can be separated from the aqueous solution of aluminum chloride in the 45 distillation flask by simple decantation. It is then taken up in carbon tetrachloride, benzene, or other organic solvent and crystallized therefrom. In the preparation of the di-substituted carbazoles, such as 2,8-distearylcarbazole, the 50 same procedure is followed with the exception that 2 mols of stearyl chloride are used instead of 1.

We can start with any acid chloride of the higher fatty acids. Generally we start with the acid 55 chlorides of fatty acids of twelve or more carbon atoms since these fatty acids are readily available and cheap. Our invention is, therefore, not limited to the specific compounds described above, since we are the first to describe aralkyl ketones, 60 or mixed ketones, in which the aryl group is a carbazole radical and the alkyl group, or groups, is the alkyl radical of a higher fatty acid.

We believe that the course of the reaction for 65 the formation of the ketones is that given above but we do not wish to be bound thereby. Likewise under some conditions it is possible that the

substituent —COR' group may take some other position than that stated. In other words isomeric compounds may form and indeed mixtures of various isomers may be prepared. Consequently we define our invention broadly in the appended claims and do not wish to be limited to specific ketones except as indicated in the claims.

All of the ketones can be prepared as described for 3-stearylcarbazole and consequently we limit the description of our procedural steps to this substance. Generally the quantities of reacting substances used are those required by stoichiometric calculation.

In the interest of uniformity in nomenclature 15 we are defining our compounds in the foregoing by means of the International nomenclature. In this method of identifying the position of substituent groups the carbon atoms are numbered beginning with the right-hand top carbon of the 20 carbazole radical and going clockwise. Thus in the International nomenclature the stearylcarbazole is identified as 2-stearylcarbazole. In the chemical abstracts nomenclature the compound would be known as 3-stearylcarbazole. And in 25 the appended claims we refer to the alkyl group in the ketone as undecyl, tridecyl, pentadecyl or heptadecyl as the case may be, since such definition is more appropriate when identifying the 30 substituent alkyl groups in the ketones. Thus, for example, that ketone wherein R' is heptadecyl is identical with 2-stearylcarbazole, that compound where R' is undecyl is identical with 2-laurylcarbazole, etc.

Having thus described our invention, what we 35 claim is:

1. An aralkyl ketone having the structure:

wherein R' is an alkyl radical chosen from the 45 group consisting of undecyl, tridecyl, pentadecyl and heptadecyl.

2. An aralkyl ketone having the structure:

wherein R' is an alkyl radical chosen from the 55 group consisting of undecyl, tridecyl, pentadecyl and heptadecyl.

3. The ketone as in claim 1 wherein R' is heptadecyl.

4. The ketone as in claim 1 wherein R' is 60 undecyl.

5. The ketone as in claim 2 wherein R' is 65 heptadecyl.

ANDERSON W. RALSTON.
